(57) **CLAIM**

The ornamental design for a casting machine part, as shown and described.

DESCRIPTION

Fig. 1.1 is a top plan view of a casting machine part showing our new design;

Fig. 1.2 is a front elevation view thereof;

Fig. 1.3 is a bottom plan view thereof;

Fig. 1.4 is a rear elevation view thereof;

Fig. 1.5 is a left-side view thereof;

Fig. 1.6 is a right-side view thereof;

Fig. 1.7 is a bottom perspective view thereof; and

Fig. 1.8 is a top perspective view thereof.
